RADIO ANTENNA SYSTEM

Thaddeus J. Dylewski, Chicago, Ill., assignor to Radio Corporation of America, a corporation of Delaware

Application August 25, 1951, Serial No. 243,628

10 Claims. (Cl. 343—845)

This invention relates to radio antennas and more particularly to antennas adapted to be operated at a number of frequencies over a wide frequency band.

When the frequency of operation of a radio antenna is varied, the effective series resistance and reactance at the antenna terminals vary cyclically, having alternate high and low values. In arrangements heretofore used and known in the art, this variation in antenna resistance and reactance with change in frequency make it necessary to provide tuning, loading, or matching apparatus between the radio receiver or transmitter and the antenna to effect an efficient interchange of energy between the antenna and the radio transducer apparatus for all frequencies at which it is desired to operate the system. Such arrangements suffer from the disadvantages of being complicated and expensive.

An object of this invention is to restrict the antenna terminal resistance and reactance to a small range of values.

Another object of this invention is to minimize and simplify antenna tuning, loading, or matching apparatus between the antenna and the radio receiver or transmitter.

Briefly, in accordance with the present invention there is provided an antenna consisting of an extended conductor over a ground plane, with feed terminals for radio receiver or transmitter apparatus at one end and a switching device between the antenna and ground at the opposite end. When the switch is open, the antenna terminal resistance and reactance vary cyclically with frequency. When the switch is closed, the antenna terminal resistance and reactance still vary cyclically, but the frequencies at which high and low values of terminal resistance and reactance occur are transposed; that is, with the switch closed, high values of terminal resistance and reactance occur at those frequencies at which low terminal resistance and reactance result when the switch is open, and vice versa.

By operating the antenna with the switch closed over a certain band of frequencies, and with the switch open over an adjacent band of frequencies, the antenna terminal resistance and reactance values can be restricted to a smaller range of variation. The selection of either high or low terminal resistance and reactance values will depend upon the characteristic impedance of the transducer apparatus (transmitter or receiver) to which the antenna is connected.

A more complete understanding of the operation and features of the invention may be gained from a reading of the following description in connection with the accompanying drawing in which:

Fig. 1 is a schematic diagram of an arrangement of the antenna of this invention;

Fig. 2 is a graphical plot of the variation of the reactance of the antenna as the frequency is varied, showing the far end both open and shorted;

Fig. 3 is a graphical plot of the variation of the antenna resistance as the frequency is varied, showing the far end both open and shorted;

2

Fig. 4 illustrates a cam surface which may be used in connection with the tuning mechanism of the radio receiver or transmitter of Fig. 1 to automatically open and close the switch at the far end of the antenna; and Fig. 5 is a schematic diagram according to this invention using a cam surface like that of Fig. 4 in connection with the tuning mechanism of a radio receiver or transmitter.

In Fig. 1 an antenna conductor 11 is shown disposed over a conductive ground plane 13. The antenna conductor 11 may be parallel to or at an acute angle to the ground plane 13. One end of the antenna conductor 11 is connected to a terminal 15, and another terminal 17 is electrically connected to the ground plane 13. These antenna input terminals 15, 17 are adapted to have connected thereto a radio transducer apparatus 19, for example a radio transmitter or receiver. At the other end of the antenna conductor 11 a switch or switching device 21 is arranged to connect the remote end of the antenna conductor 11 directly to the ground plane 13. The ground plane 13 may consist of the earth, a counterpoise, the electrically conductive structure of an aircraft, ship, vehicle, or fixed installation, or other electrically conductive surfaces, frameworks, or bodies in the near zone of the antenna which jointly or severally complete the conduction circuit of the antenna.

The switching device 21 may be a simple manual switch controlled at the end of the antenna 11 remote from the radio transducer apparatus 19 but preferably is controlled by a relay 23 which may be actuated by a switch key 25 at the location of the radio transducer apparatus 19 to supply the necessary operating current over a pair of conductors 29 from a source of potential 27, such as a battery, generator, or the like. The path from the remote end of the antenna 11 through the switch 21 to the ground plane 13 may be considered a non-dissipative connection, that is, one having a negligible resistance component.

Although the antenna conductor 11 is shown on the drawing as inclined at an angle to the ground plane 13, it will be understood that similar variations of antenna terminal resistance and reactance obtain with other configurations such as parallel to the ground plane 13, and that this invention is operable with other geometric patterns of antenna conductors where the ground plane 13 is in the near zone of the antenna conductor 11.

In an antenna in accordance with this invention for installation on an aircraft, the following dimensions are representative. The length of the antenna conductor 11 may vary between 25 and 85 feet, depending on the type and size of the aircraft upon which the antenna is installed. For aircraft communication in the operating frequency band from 2 to 24 megacycles, the wavelength of the free space wave varies from 41 feet to approximately 492 feet. It will thus be seen that the antenna on some installations will be longer than one wavelength at the highest frequency in the operating range, while at the lowest frequency it will be a fraction of one wavelength.

The switching device 21 is preferably mounted in a rear support member which is secured to the rudder support or vertical stabilizer of the aircraft at a point from 5 to 30 feet above the fuselage of the aircraft. The antenna conductor 11 is customarily made of copper-clad steel wire of No. 10 gauge which is covered with a polyethylene coating to prevent corrosion. The spacing of the antenna conductor 11 from the fuselage of the aircraft at the end nearest the radio transmitter and receiver apparatus is usually somewhat smaller than that at the remote end. It may be, for example, from less than 2 to more than 6 feet above the fuselage or conductive surface of the aircraft. This dimension also depends upon the type of aircraft on which the antenna of this invention is installed.

and may be determined by optimum measurements obtained during a trial and error procedure.

Referring now to Fig. 2, which is a graphical representation of the variation of the reactance of an antenna as the frequency is varied, there are shown two curves. One curve 31, represented by an open pair of lines, shows the variation of reactance at the antenna terminals 15, 17 when the remote end of the antenna conductor 11 is open or ungrounded. It will be noted that the curve for the open end condition varies widely, extending from about 10,000 ohms positive reactance to 10,000 ohms negative reactance with a very steep slope portion between these extremes. A second curve in Fig. 2, the area of which is hatched and labeled with the reference character 33, illustrates the limits of variation of reactance of the antenna of Fig. 1 at the terminals 15, 17 with the far end shorted by the switching device 21.

It will be seen that the curves 31, 33 of Fig. 2 are similar in shape, but corresponding portions of their slopes occur at different points in the frequency band.

The curves of Fig. 2 represent actual data taken from an antenna having a length of 50 feet, spaced 8 feet above and parallel to a ground plane, and operated over a frequency range from 2 to 24 megacycles. One of the factors determining the magnitude of variation of reactance is the spacing of the antenna conductor 11 from the ground plane 13. Curves like those shown in Fig. 2 will be obtained for all reasonable spacings of antenna and ground plane.

Fig. 3 shows a graphical representation of the variation of the antenna resistance as the frequency is varied, with one curve 35 representing the conditions at the antenna terminals when the far end is open, and a second curve 37 representing the conditions at the antenna terminals when the far end is shorted to the ground plane 13. The curve 35, indicated by an open pair of lines, represents the antenna resistance over a band of frequencies from 2 to 24 megacycles with the far end open, that is, not connected to ground. It will be noted that the curve 35 has three low resistance portions and two very high resistance portions. The second curve 37, the area of which is hatched, has three high resistance portions in the band of frequencies shown, but these occur at frequencies different from the very high resistance portions of the first curve 35.

The data from which the curves of Fig. 3 were plotted were obtained experimentally under conditions identical with those described above in connection with Fig. 2.

By operating over a part of the frequency band with the switch 21 of Fig. 1 open at the far end of the antenna 11, and over another portion of the band with the switch 21 at the far end of the antenna closed to short-circuit the remote end, the range of variation of antenna resistance and reactance can be greatly restricted.

The tuning and matching apparatus necessary in such a system can be greatly simplified and minimized by restricting the variation of resistance over the band to a narrower range than is obtainable without switching, for example to the range from 10 to 1,000 ohms. This is accomplished in accordance with this invention by operating the apparatus with the remote end of the antenna 11 short circuited over the portion from 2 to approximately 3 megacycles, open-circuited from approximately 3 to approximately 7 megacycles, short-circuited from that point to about 12½ megacycles, and so on, always following those portions of either the shorted end or the "open end" curves in Fig. 2 or 3 which fall within the limits of variation tolerable in the particular equipment with which the antenna is associated. Matching apparatus which is required to match a reactance variation of 20,000 ohms or an antenna resistance variation of from 1 ohm to 50,000 ohms is of necessity much more complicated and expensive than matching apparatus which is capable of matching a reactance variation of only 2,000

ohms or an antenna resistance variation of 10 ohms to 1,000 ohms.

In Fig. 4, there is illustrated a cam surface which may be used in cooperation with the tuning mechanism of the radio receiver or transmitter 19 to control the opening and closing of the switch 21 at the far end of the antenna 11 shown in Fig. 1. The cam surface is indicated generally by the reference characters 39 and 41 and is represented for the same frequency range and conforms to the abscissa scale of Figs. 2 and 3 shown immediately above. The lower or indented portions 39 of the surface allow a cam follower to open the contacts of the switch key 25 of Fig. 1. When the cam follower, which cooperates with the cam surface shown in Fig. 4, engages the raised portions 41 of the cam surface, the contacts of the switch key 25 will be closed, which in turn actuates the relay 23 of Fig. 1 to short the remote end of the antenna conductor 11 to ground.

An examination of the cam surface 39, 41 of Fig. 4 and a comparison with the reactance and resistance curves of Figs. 2 and 3 will show that the cam surface has been designed to provide a low antenna resistance throughout the band of frequencies shown. A much higher resistance range would of course be obtained by reversing the indented portions 39 and the raised portions 41 of the cam surface shown in Fig. 4.

Fig. 5 shows the antenna of this invention installed on an aircraft which utilizes the cam arrangement of Fig. 4 in cooperation with the tuning mechanism of a radio receiver transmitter 19 of Fig. 1. The cam surface 39, 41 is shown on a shaft 43 which operates in cooperation with or controls a tuning element, such as a variable capacitor 45 in the radio apparatus 19. A cam follower 47 engages the cam surface 39, 41 and, by the movement of the cam follower 47, determines whether the contacts of the switch key 25 are open or closed for the particular tuning adjustment controlled by the shaft 43. The switching device 21 is shown in this figure as contained in the vertical stabilizer of an aircraft having a conductive surface 13' as described above in conjunction with Fig. 1. As indicated schematically in Fig. 1, the antenna conductor 11 is maintained in insulated relationship to the surface of the aircraft or ground plane 13' of Fig. 5.

Instead of the cam control of the switching device 21, the actuation of the switch 21 at the remote end of the antenna may be performed by sensing the voltage appearing across the antenna terminals 15, 17 when the antenna is being used for transmitting. The voltage at the antenna terminals 15, 17 will change throughout the band due to the variation of the antenna resistance and reactance. At a frequency which has been selected for transmitting, the voltage across the antenna terminals 15, 17 may be compared either manually or automatically for both open and closed positions of the switch 21 with the optimum transmitter output voltage, and the switch position which gives a voltage more closely approximating the value of the optimum output voltage is selected.

It will thus be seen that the arrangement of this invention permits the use of a single antenna for transmitting or receiving any of a great number of frequencies over a very wide frequency band. By operating the antenna with the switch either open or closed, depending upon the frequency, the antenna terminal resistance and reactance are restricted to a smaller range of values. This simplifies and minimizes the antenna tuning, loading, and matching apparatus which must be provided between the antenna and the radio receiver or transmitter.

What is claimed is:

- An antenna switching system for an antenna operable at a plurality of frequencies over a wide frequency band comprising an antenna conductor, a conductive surface, said conductive surface being in the near zone of said antenna, radio transducer apparatus having tuning means

associated therewith, said radio transducer apparatus being coupled to one end of said antenna conductor and to said conductive surface, switching means directly connected between the other end of said conductor and said conductive surface, and control means for said switching means actuated by said tuning means of said transducer apparatus.

2. An antenna switching system as defined in claim 1 in which said control means comprises a cam surface mechanically coupled to said tuning means, a keying switch under the control of said cam surface, a relay operative upon the closing of said keying switch to close contacts constituting said switching means.

3. An antenna switching system as defined in claim 2 in which said antenna conductor has a length exceeding one wavelength at the highest operating frequency and less than one wavelength at the lowest operating frequency.

4. An antenna switching system as defined in claim 2 in which said conductive surface comprises the conductive surface of an aircraft.

5. An antenna system comprising a conductive surface, an elongated conductor extending in a straight line from one end thereof to the other and mounted in spaced relation with said conductive surface, antenna terminals 25 for connection to a radio equipment including a terminal connected to said one end of said conductor and a terminal connected to an adjacent point on said conductive surface, and a switch having a closed position connecting the other remote end of said conductor to a point on said conductive surface adjacent said remote end, and having an open position completely isolating said remote end of said elongated conductor.

6. An antenna system as defined in claim 5, wherein said points on said surface are spaced by substantially the 35 same distance as the length of said conductor.

7. An antenna system as defined in claim 5, wherein said conductor has a length exceeding one wavelength at the highest operating frequency and less than one wavelength at the lowest operating frequency.

8. An antenna system as defined in claim 5, wherein said conductive surface comprises the conductive surface of an aircraft.

9. An antenna system as defined in claim 5, wherein said straight wire conductor generally forms an acute angle with said conductive surface.

10. An antenna operable at a plurality of frequencies over a frequency range from approximately 2 to 24 megacycles comprising an elongated conductor having a length of from 25 to 85 feet, a ground plane comprising a conductive surface of an aircraft in the near zone of said antenna conductor, radio transducer apparatus having tuning means associated therewith, said radio transducer apparatus being coupled to one end of said antenna conductor and to said conductive surface, switching means directly connected between the other end of said conductor and said conductive surface, and control means for said switching means actuated by said tuning means of said transducer apparatus.
